UNITED STATES PATENT OFFICE

LEONARD D. SOUBIER, OF TOLEDO, OHIO, ASSIGNOR TO OWENS-ILLINOIS GLASS COMPANY, A CORPORATION OF OHIO

GLASSWARE ANNEALING LEER

Application filed July 16, 1930. Serial No. 468,943.

The present invention relates to improvements in glassware annealing leers and has for an object the provision of novel means for cooling the leer tunnel in the area beyond or rearwardly of the "heating zone."

In the art of annealing glassware, such for example as bottles and jars, the ware is placed in the receiving end of a tunnel and by means of a conveyor therein is carried through said tunnel to a delivery end where operators remove the articles of glassware from the conveyor for packing. The heat within the tunnel at and in proximity to the receiving end thereof is sufficiently great to bring the temperature of the ware to a point at which any strains or stresses in the glass structure are removed. From this zone (commonly called the "heating zone") rearwardly, the temperature in the tunnel gradually decreases, the temperature gradient being such that strains and stresses of any appreciable degree, do not reappear in the glass, and the articles therefore leave the leer in condition to withstand the hard usage to which they are subjected. Below a predetermined point rapid cooling of the glassware does not detrimentally affect the character and strength of the glassware. Accordingly, artificial cooling is frequently, and in fact generally, employed to bring the temperature of the glassware down to a point at which the operators may readily handle the ware for packing.

An object of the present invention is the provision of novel means for cooling the leer tunnel and therewith means by which the effectiveness of the cooling means may be controlled and regulated both as to the zone affected and degree of cooling obtained. To this end the invention comprises the provision of a series of chambers or compartments extending across the leer roof and in fact forming said roof, and the further provision of means whereby a cooling medium may be introduced into any or all of the chambers or compartments in regulable quantities.

Another object is the provision of novel means for controlling the effectiveness of the cooling medium in any or all of the chambers

or compartments. To this end the cooling medium is forced through the chambers, entering at opposed points and exhausting at a point midway between the inlet points, the inlets and outlets being provided with means for controlling the rate of movement of the medium therethrough.

Other objects will be in part apparent and in part pointed out hereinafter.

In the drawings:

Fig. 1 is a fragmentary side elevation of a leer embodying my invention.

Fig. 2 is a fragmentary plan view illustrating in detail the blower and compartments or chambers connected thereto.

Fig. 3 is a detail plan view showing several of the chambers and associated parts.

Fig. 4 is a detail perspective view showing the manual control for the dampers controlling inlet of the cooling medium to the chambers.

Fig. 5 is a transverse sectional view taken substantially along the line V—V of Fig. 3.

Fig. 6 is a sectional view taken substantially along the line VI—VI of Fig. 5.

In the illustrated embodiment of the invention, the leer comprises an elongated tunnel 10 supported on wheels 11 so that the entire leer may be moved as a unit relative to a ware forming machine (not shown). The tunnel may include sheet metal bottom and side walls 12 and 13 respectively entirely encased in suitable insulating material 14. An endless reticulated conveyor 15 has a ware bearing reach extending through the leer tunnel and supported in spaced relation to the bottom 12 on rollers 16 and in guide ways 17. The return reach of the conveyor is disposed below and outside of the leer tunnel and may be supported by the rollers 18 spaced apart lengthwise of the leer. This conveyor is continuously and slowly moved through the tunnel by a motor driven mechanism (not shown) whereby the articles of glassware to be annealed are transported through the heating and cooling zones A and B respectively, in the leer. Any suitable heating means (not shown) may be employed to heat the tunnel.

According to the present invention the

- cooling zone includes a roof composed of a series of chambers 19 extending transversely of the leer and at least partially, if not completely, encased in insulating material. 5 These chambers (Fig. 5) are supported directly on the upper ends of the side walls 13. Each chamber is provided with a pair of opposed inlet ports 20 at its ends connected to headers 21 through branch pipes 22, said headers 10 extending rearwardly along side the leer tunnel and connected to a blower 23 which is operated by a motor 24. A cooling medium is forced into the headers 21 by the blower 23 and enters the chambers through the opposed inlet ports 20. Dampers 25 in the branch pipes 22 are adjustable to regulably control the volume of cooling medium entering the chambers. Each pair of dampers are adjusted by means including a shaft 26 extending transversely above the leer tunnel (Fig. 5), said shaft having beveled gears 27 on its ends, running in mesh with gears 28 at the upper ends of spindles 29 which carry said dampers 25. One shaft 29 of each pair (Figs. 1 and 5) carries a beveled gear 30 at its lower end just below the corresponding branch pipe 22, said gear adapted at times to mesh with a beveled gear 31 on a control shaft 32. This control shaft 32 extends lengthwise along one side of the leer tunnel and is journaled at spaced points in bearings 33. Coil springs 34 encircling the shaft 32 between said gears 31 and adjacent bearings 33 operate to yieldingly hold said gears out of mesh with the gears 30 so that the operator may individually adjust the angular positions of the dampers 25. Thus the dampers regulating the inflow of cooling medium to the chambers may be adjusted as required by operating conditions, to obtain varying degrees of cooling. Further, after a predetermined cooling curve has been established, all points of this curve may be raised or lowered corresponding degrees, 45 merely by moving the control shaft 32 lengthwise, causing the gears 30 and 31 to mesh with one another and then rotating the control shaft so that the angular positions of the dampers 25 are changed.
- 50 Exhaust of the cooling air from each chamber 19 takes place through an outlet port 35 (Fig. 5) arranged in the upper wall of the chamber midway between the inlet ports 20. Exhaust of the cooling air is regulated by a damper 36 to further control its effectiveness in cooling the leer tunnel. Each damper comprises two plates 37 hinged at their lower ends to a shaft 38 extending transversely of the chamber substantially at its center. This shaft (Fig. 6) may be journaled at its opposite ends in bearings 39 attached to the side walls of the chambers. These damper plates 37 extend upwardly through the exhaust port 35 and are connected at their upper ends through links 40 to a lever 41, the latter pivoted to a hinge pin 42 on a bracket 43 rising from the roof of the leer. The outer end of this lever 41 is connected through a cable 44 to a counterweight 45 whose weight is sufficient to substantially balance that of the damper plates. Thus the counterweight holds the damper 36 in any adjusted position.
- 55 In order to substantially balance temperature conditions transversely of the leer in the cooling zone, the lower walls 46 (Fig. 5) of the cooling chambers 19 (constituting the roof of the tunnel) are declined transversely of the tunnel toward the center so that the heated gases rising in the central portions of the leer tunnel will be divided and moved in opposite directions into the side areas 10^a of said tunnel. Thus these areas which ordinarily are considerably cooler than the central portion, will be sufficiently heated to maintain a substantially balanced temperature condition transversely of the leer tunnel, and as a result assist materially in obtaining uniform annealing of glassware.
- 60 Modifications may be resorted to within the spirit and scope of the appended claims.
- What I claim is:
1. In a glassware annealing leer, a tunnel having ware heating and cooling zones, a series of cooling chambers extending transversely of the leer in the cooling zone, each chamber having opposed ports at its ends and a port centrally disposed between said opposed ports, and means without the leer tunnel causing flow of a cooling medium through the chambers and ports. 95
  2. In a glassware annealing leer, a tunnel having ware heating and cooling zones, a series of cooling chambers extending transversely of the leer in the cooling zone, each chamber having opposed ports at its ends and a port centrally disposed in its upper side, means without the leer tunnel causing flow of a cooling medium through the chambers and ports, and means individual to the ports for regulating the rate of flow of the cooling medium therethrough. 100
  3. In a glassware annealing leer, a tunnel having heating and cooling zones, a series of chambers extending across the tunnel and forming the roof of the cooling zone, each chamber having opposed inlets at its ends and an outlet centrally disposed in its upper side, dampers for the inlets and outlet, and means causing a flow of cooling medium through the chambers. 115
  4. In a glassware annealing leer, a tunnel having heating and cooling zones, chambers extending transversely of and constituting at least a part of the roof in the cooling zone, each chamber having an inlet at each end for a cooling medium, means for introducing a cooling medium into each chamber, an outlet for the cooling medium, and adjust- 125

able means for controlling exhaust of the medium through said outlet.

5. In a glassware annealing leir, a tunnel through which ware is carried and annealed, said tunnel including heating and cooling zones, chambers extending transversely of and constituting at least a part of the roof in the cooling zone, each chamber having inlets for cooling air at the ends, and an outlet near its center, dampers for the inlets, means for adjusting all of said dampers simultaneously, dampers for the outlets, and means for individually adjusting the dampers in the outlets.
15. 6. In a glassware annealing leir, a tunnel through which ware is carried and annealed, said tunnel including heating and cooling zones, chambers extending transversely of and constituting at least a part of the roof in the cooling zone, each chamber having inlets for cooling air at the ends, and an outlet near its center, dampers for the inlets, means for adjusting all of said dampers simultaneously to change the effectiveness of all the chambers corresponding degrees, means whereby the dampers may be individually adjusted, and means for regulating exhaust of the cooling medium through the outlets.
25. 7. In a glassware annealing leir, an elongated tunnel through which glassware is car-

ried and annealed, a floor for the tunnel, a conveyor for transporting glassware through the tunnel, said tunnel including a metal roof having its marginal areas spaced a greater distance from the conveyor than its central area, whereby hot gases rising in the central portions of the tunnel are divided and caused to move into the side areas of said tunnel, and means for causing flow of a cooling medium over the upper surface of the roof and inwardly from the opposed margins thereof.

8. In a glassware annealing leir, a tunnel having heating and cooling zones, a series of box-like metal chambers extending across the tunnel and forming the roof of the cooling zone, each chamber having opposed ports at its ends and a port centrally disposed in its upper side, dampers for said ports, and means causing a flow of cooling medium through the chambers and ports.

9. A glassware annealing leir comprising a tunnel having a metallic wall, a series of open ended flues extending transversely of the tunnel on one side of the wall, and means for causing movement of a cooling medium through the flues to control the temperature in said tunnel.

Signed at Toledo, Ohio, this 14th day of July, 1930.

LEONARD D. SOUBIER.
